UNITED STATES PATENT OFFICE.

RENÉ JEAN CAMILLE TAMPIER, OF BOULOGNE-SUR-SEINE, FRANCE.

FEEDING APPARATUS FOR INTERNAL-COMBUSTION MOTORS.

1,296,229.

Specification of Letters Patent.

Patented Mar. 4, 1919.

Application filed October 21, 1918. Serial No. 253,926.

To all whom it may concern:

Be it known that I, RENÉ JEAN CAMILLE TAMPIER, citizen of the Republic of France, and resident of Boulogne-sur-Seine, France, (post-office address 1 Rue de Bellevue,) have invented a new and useful Feeding Apparatus for Internal-Combustion Motors, which improvements are fully set forth in the following specification.

10 This invention relates to feeding apparatus for internal combustion motors, based on the use of a carbureter without steady level, the nozzle of which communicates directly with a tank placed below it, from 15 which the gasolene required for working the motor is being sucked.

In the annexed drawing:

Figure 1 is a diagrammatic view of the apparatus, and
20 Fig. 2 relates to a development of the invention.

The in-take manifold of the motor 1 is connected to a carbureter 2 without steady level, into which a nozzle 3 opens, said 25 nozzle communicating at its lower end with a horizontal pipe 4 to which an elevated supply tank 5 is connected. This tank has a depending outlet pipe which leads to pipe 4 and is provided with a cock 6.

30 A second or relief tank 7 is placed in rear of, and at a lower level than the nozzle 3 and has connected to its bottom an upwardly extending pipe which is also connected to pipe 4, hydrocarbon being supplied to pipe 4 and hence to nozzle 3, when cock 8 is opened.

35 The whole device works in the following way: To start the motor, the cock 6 is opened, the gasolene flowing by gravity to the 40 nozzle through the pipe 4.

The motor having started to run, and suction being created in the tank 5, the cock 8 is then opened, whereupon a part of the gasolene from the tank 5 begins to flow into the tank 7, this being insured by the 45 arrangement of the sections of the pipework.

The cock 6 is then shut. The motor still running now sucks in gasolene through the 50 nozzle 3 from the lower tank 7.

Fig. 2 shows an improvement of the device described above, in case it should be preferred to use the tank 5 as a relief tank, instead of using it only for starting the motor; this tank being placed higher than 55 the tank 7, the quantity of gasolene being sucked by the motor from the tank 7 will be less than that supplied by the tank 5.

To obviate this, the carbureter has connected to it a second nozzle 9 communicating with the tank 7. When the cock 8 is open, the cock 6 shut, and the cock 12 open, the gasolene is sucked by the nozzle 3 and the extra nozzle 9.

Claim:

A feeding apparatus for internal combustion motors, comprising a nozzle, two hydrocarbon tanks communicating with the nozzle, one of which is placed at a higher level, the second at a lower level than the 70 nozzle, means to effect communication between both tanks and the nozzle, an extra nozzle adjacent the first nozzle, and means to effect communication between the extra nozzle and the lower tank whereby an extra 75 amount of hydrocarbon is delivered to the motor when fed from the lower tank.

In testimony whereof I have signed this specification.

RENÉ JEAN CAMILLE TAMPIER.
